AIRSHIP

Alex A. Rommel, Fresno, Calif.

Application April 6, 1959, Serial No. 55,349

Term of patent 7 years

(Cl. D71—1)

FIG. 1.

FIG. 2.

Fig. 1 is a side elevation of an airship, showing my new design. The appearance of the airship is the same on all sides as indicated in Fig. 2.

Fig. 2 is a top plan view of the airship.

The dominant features of the design reside in the portions shown in full lines.

I claim:

The ornamental design for an airship, as shown and described.
